APPARATUS FOR WETTING A ROLL OF PRE-PASTED WALLPAPER

Harry A. Reid, Oak Park, and John C. Gall, Chicago, Ill., assignors to Sears, Roebuck and Co., Chicago, Ill., a corporation of New York

Application July 7, 1954, Serial No. 441,894

4 Claims. (Cl. 118—419)

This application is in part a continuation of our application S.N. 405,544, filed January 22, 1954, now abandoned.

Pre-pasted wallpaper is old and is becoming more and more popular for use by the householder, inasmuch as it is more convenient to apply than ordinary wallpaper which requires space consuming apparatus and special skill for the application of paste and proper hanging and is likely to be more messy. As heretofore used, pre-pasted wallpaper has been moistened in a sink or other container of water, the operation usually requiring unrolling and re-rolling in the water in order that the adhesive might be effectively moistened. This operation as usually practiced by the housewife is inconvenient and, unless properly performed, the adhesive may be inadequately prepared and the hanging is likely to be unsuccessful.

Our invention contemplates a special container for the preparation of pre-pasted wallpaper. According to our invention, there is provided a relatively small container of such size as convenient to hold a roll of pre-pasted wallpaper and sufficient water to cover and moisten the same. This container is open at the top and is provided with means for retaining the roll under water in the container and also means for guiding a web of such paper through a relatively extended path under water before it emerges from the container, to insure thorough wetting of the adhesive. Thus, in accordance with our invention, the container with the roll of paper and water may be disposed on the floor closely adjacent the wall where the paper is to be applied and it will merely be necessary to draw the web of paper upwardly from the container to the wall surface to which it is to be applied and then to proceed immediately to apply the paper to the wall in the usual manner, cutting the strip off outside of the container and repeating the operation, strip by strip, until the job is completed. Obviously, such an operation may be accomplished with the utmost convenience and without splattering water or adhesive around the room.

As a variation in our invention we also contemplate a container for water generally similar to the one just described except that in lieu of having means for moistening a roll of wallpaper under water, we provide means for moistening said roll in an elevated position, so that the roll remains dry until it is desired to moisten it and apply it to the surface which is to be papered.

Our invention also contemplates that the apparatus may be made of inexpensive materials, being preferably of waterproof cardboard or the like, so that at slight expense a container may be provided for a single paper hanging operation and then be scrapped.

Various other advantages will become apparent as the description proceeds.

Turning now to the drawings forming a part of this specification and illustrating certain preferred embodiments of our invention:

Fig. 1 is a perspective view of one embodiment of our invention, the walls being broken away in order that the invention may be more clearly understood;

2

Fig. 2 is a transverse sectional view of the same taken substantially along the line 2—2 of Fig. 1;

Fig. 3 is a perspective view similar to Fig. 1, showing another embodiment of our invention;

Fig. 4 is a perspective view of still another embodiment;

Fig. 5 is a perspective view showing in use an apparatus according to any of the embodiments of our invention;

Fig. 6 is another "use" view at a later stage in the operation;

Fig. 7 is a perspective view of another embodiment of our invention wherein means is provided for supporting a roll of wallpaper in an elevated position rather than under water;

Fig. 8 is a transverse sectional view of the article shown in Fig. 7;

Fig. 9 is a fragmentary, longitudinal, sectional view of the same taken substantially along the line 9—9 of Fig. 8;

Fig. 10 is a perspective view similar to Fig. 7 showing another construction for supporting the roll in an elevated position;

Fig. 11 is a similar view illustrating still another version of the same; and

Fig. 12 is a transverse sectional view similar to Fig. 8 of the version shown in Fig. 11.

Referring first to Figs. 1 and 2, our invention contemplates a rectangular open topped container indicated generally by the numeral 10, having end walls 12, 12, a front wall 15, and a rear wall 16. This container may be formed of any relatively inexpensive material and may, for example, be molded out of papier maché and provided with a waterproof coating, and is slightly longer in its major dimension than a roll of wallpaper. Disposed within the container 10 and preferably integral therewith is an angular guide member 18 having a bottom leaf 19 and an upstanding leaf 20, the latter being spaced from the front wall 15 as by the aperture 22. Thus angular member 18 is attached to the front wall 15 of the container 10 and may or may not be attached to the end walls. The free edge 25 of the bottom leaf 19 of the angular member is spaced from the wall 16 of the container.

Turning to the embodiment of Fig. 3, we provide in this case an open top rectangular container 10a, which may be substantially the same in overall dimensions as container 10, described above, being slightly longer than the axial length of a roll of wallpaper. In this case we may provide a simple cardboard box, preferably waterproof. Disposed within the container 10a, is a rack indicated generally by the numeral 30, comprising a pair of inverted V-shaped brackets 32, disposed at each end of the container, which brackets may, if desired, terminate in laterally projecting bights 35, which bights may be supported on the top edges of the end walls of the container or might extend through apertures therein.

A bar 38 connects one of the legs of each of the V-shaped brackets while the other legs each have an extension, 40, 40 which extensions are preferably relatively short so as to provide pintles or bearings for supporting a roll of wallpaper. In lieu of providing pintles 40, a bar corresponding to bar 38 may extend between the V-shaped brackets at the rear as well as the front thereof, such a bar providing a stop or abutment for a roll of wallpaper, functioning in the same manner as the front edge 25 of the wall 19 in the embodiment of Figs. 1-2.

Fig. 4 shows another embodiment having a wire rack 30' of U formation, the free ends of the wire rack having hooks 50 engageable in notches in the side wall of the box.

In the use of either of the embodiments above described a roll of pre-pasted wallpaper is placed in the container and the web thereof is fed along the bottom and up the

front wall 15 thereof, as seen in Fig. 5. Thus, in the embodiment of Fig. 1, the web is drawn under the wall 19 and then upwardly through the slot 22. If the guide member is unattached at the sides, it may be elevated to facilitate placing the roll in the container. In the embodiment of Fig. 3 the rack 30 may be withdrawn from the box and the pintles 40 sprung apart to facilitate placing them in the roll. In the embodiment of Fig. 4, likewise the roll is placed to one side of bar 55 and the paper web drawn thereunder. The web is then drawn under the bar 38 or 35 so that it extends along the bottom wall of the container and is then drawn upwardly and out of the container. This stage of the operation, as seen in Fig. 5, may conveniently be performed on a table T.

The operator is now ready to begin hanging. The container is then placed on the floor adjacent the area to which the paper is to be hung and the paper is then drawn upwardly out of the container to the uppermost position on the wall area to which the strip is to be hung and is then applied in the usual manner, wiping the paper downwardly with a brush or sponge in accordance with the usual paper hanging process.

Fig. 6 illustrates the operation near the end of application of a strip. At about this point the operator will cut off the strip outside the container and finish the application of that strip to the wall surface and will repeat the operation until the entire wall has been covered.

It will readily be seen that we have provided a simple and inexpensive piece of apparatus which will greatly facilitate the operation of home hanging of pre-pasted wallpaper, whereby such material may be used with a minimum of mess and bother and with practically no disturbance of the usual household furnishings. By drawing the paper through an extended path under water before withdrawing it from the container, thorough wetting of the adhesive is assured—a condition important to the success of hanging pre-pasted paper.

We have found that it is sometimes desirable to support the roll of wallpaper above the water in the container rather than submerge it in the water. This is especially true when it is desired to hang only a portion of a roll at one time, the remainder of the roll being reserved for later utilization. We have found that in such instances, if the entire roll has been submerged and the adhesive thereon has become moistened, adjacent convolutions of the roll may become stuck together so that it may be necessary, when at some later time it is desired to use said paper, to submerge the entire roll for 30 minutes or more before the paper can be unrolled.

In the embodiment shown in Figs. 7, 8 and 9 we employ a container 60 which, as in the other examples, may be formed of inexpensive materials such as waterproof cardboard, or the like, said container being in the form of an open top elongated rectangular trough having integral outwardly extending lips or flanges 62 at the front and rear thereof.

Supported by the top edges of the side walls of the container is a pair of trunnions 65 for supporting a roll of wallpaper R. These trunnions, as seen best in Fig. 9, comprise a U-shaped loop 67 having connected thereto an upwardly disposed angular support 69. These trunnions are preferably formed of bent wire or the like. If desired, the top edges of the side walls of the container may be notched or apertured to form seats for the trunnions 65. Also supported by the side walls of the container 60 is a U-shaped rack 70 having a bar portion 71 approximately equal to the length of the container 60 and normally disposed adjacent the bottom thereof and serving as a guide for the web of wallpaper which is being moistened for application to a wall surface, as seen best in Fig. 8. The U-shaped member 70 has reversely bent loops 72 engaging the top edges of the said wall, and the latter may likewise be notched or apertured to receive said loops.

It will be seen that, according to this embodiment of

our invention, the paper supported on the trunnions 65 is kept entirely dry until it is desired for use, at which time it may be drawn under the guide member 70 for moistening and then applied to the wall surface and cut off to provide the desired length, as described above.

If the entire roll is not consumed at one time, no harm is done to the remaining paper, which remains dry and will be immediately ready for use at a later time.

In the variation shown in Fig. 10 of the arrangement just described, we provide a U-shaped guide bar portion 76' which is integrally connected to trunnions 65' by connecting bar portions 75. In this case the guide bar portion provides a substantial brace for the trunnions, being integral therewith.

In the version of our invention shown in Figs. 11 and 12 we provide a U-shaped guide member 80 looped over the side walls of the container and extending across the sides as at 82, in substantially the same manner as in the embodiment of Fig. 10. However, instead of projecting inwardly of the container to form integral trunnions, the wire or like member extends upwardly to form loops 85, open at the top thereof to provide seats for a rod 87 extending across the top of the container to provide an axle or bearing to support a roll of wallpaper. In this embodiment a roll of paper is disposed on the rod 87 which may then be seated in the loops 85.

Various changes coming within the spirit of our invention may be made without departing from the essential spirit or scope thereof. We do not wish, therefore, to be limited to the particulars of the present specification and drawings nor by the language chosen in the foregoing description, except to the extent indicated in the appended claims.

We claim:

1. Apparatus for wetting pre-pasted wallpaper comprising an open-top water-resistant container of a length at least equal to the width of a roll of pre-pasted wallpaper, said container having front, rear, side and bottom walls, means supported by said container for rotatably mounting a roll of wallpaper in the upper portion of said container, and means also supported by said container for guiding a web of paper drawn from said roll toward the lower portion of said container to insure moistening thereof, said guide means comprising a U-shaped member extending downwardly into the container and having looped portions carried by the side walls of said container, the roll supporting means comprising a rod seated in said last mentioned loops.

2. Apparatus for wetting a roll of pre-pasted wallpaper comprising a disposable open-top container of flexible waterproof sheet material having a bottom with front, rear and opposite end walls extending upwardly therefrom to delineate a receptacle of rectangular prismatic outline having a length slightly greater than the length of the roll of pre-pasted wallpaper, said container adapted to contain a liquid for moistening the pre-pasted wall paper as it is led from the open top of said container, and a U-shaped wire member conforming substantially to the longitudinal section of the container and provided with lateral projections in engagement with the end walls of said flexible container to stabilize the upright positioning of said end walls against the hydrostatic pressure of the liquid within the container, and the base of said wire member extending adjacent to the bottom of said flexible container with sufficient clearance therefrom to permit the web of wallpaper to be moistened as it is led from the roll of wallpaper along the bottom of the container and upwardly therefrom beyond said wire member.

3. A device as set forth in claim 2 wherein the lateral projections of the U-shaped wire member are turned outwardly in loops and are supported by the upper edges of the end walls of said container.

4. A device as set forth in claim 2 wherein the lateral projections of the U-shaped wire member are turned

outwardly in loops and are supported by the upper edges of the end walls of said container, and integral continuations of lateral projections extending for a portion of said continuations in parallel to said end walls to form spaced supports for the roll of wallpaper along an axis displaced from the plane of said U-shaped wire member.
